UNITED STATES PATENT OFFICE.

JOHN W. DOWNING, OF ROCKFORD, ILLINOIS.

CARD-INDEX SYSTEM.

1,340,384.

Specification of Letters Patent. Patented May 18, 1920.

Application filed March 5, 1919. Serial No. 280,717.

To all whom it may concern:

Be it known that I, JOHN W. DOWNING, a citizen of the United States, residing at Rockford, in the county of Winnebago and 5 State of Illinois, have invented certain new and useful Improvements in Card-Index Systems, of which the following is a specification.

The invention relates to card index systems, and has for one of its objects the provision of a card index of improved construction having means for guarding against the commission of errors in filing, each card being provided with a plurality of notches 10 positioned in accordance with data on the card which determines where it is to be filed.

A further object of the invention is to provide a card index system having in combination with a card index of the character indicated, means for enabling the rapid and accurate formation of the notches in the cards.

The objects of the invention thus generally stated, together with other and ancillary advantages, are obtained by the construction and arrangement illustrated in the accompanying drawings. It will be understood, however, that in the construction of the appended claims, I do not intend that the invention shall be limited to the particular construction and arrangement illustrated and hereinafter described except as may be necessitated by the state of the prior art.

35 In the drawings, Figure 1 is a top plan view of a card index embodying the features of my invention, most of the cards being removed for the sake of clearness. Fig. 2 is a transverse, sectional view taken 40 of line 2-2 of Fig. 1. Fig. 3 is a fragmentary, sectional view, on an enlarged scale, taken in the plane of line 3-3 of Fig. 1. Figs. 4 to 7 are plan views illustrating the manner of positioning the 45 notches in accordance with the data on the cards, to insure that the cards shall be properly filed. Fig. 8 is a plan view of the means for forming the notches in the cards.

50 For convenience the invention is herein illustrated and described in connection with a card index used for filing cards according to the States of the United States and to the cities of such States, a separate section in the index being allotted to each State. Only a few of such sections, how-

ever, are shown in the card index illustrated. Thus, referring to Fig. 1, the casting 1 is shown as being provided with six partitions 2, dividing the case into five 60 sections *a*, *b*, *c*, *d*, and *e*, adapted to receive cards *x*, for the States Illinois, Michigan, Minnesota, Ohio and Wisconsin, respectively, (Figs. 2 and 4 to 7). In Fig. 1 cards are shown as filed in section *d* only, 65 the cards of the other sections not being shown for the sake of clearness.

In order that the cards for a given State shall be properly filed, each section of the case is provided on the bottom thereof with 70 a pair of bars or ribs 3 and 3^a spaced apart, and each of the cards to be filed in that section is provided in its lower edge with a pair of notches 4 and 4^a correspondingly spaced apart. Two ribs are provided 75 in order that a plurality of combinations may be made to avoid the necessity of providing a differently located rib for each of the forty-eight States as would be necessary if one rib only were provided for each 80 State. Herein I have arranged all of the States into three sets so that the cards of the States of a given set have their notches 4 located in the same position in the edge of the card and the corresponding sections 85 of the case adapted to receive such cards, have their ribs 3 positioned alike. The notches 4^a, however, of the cards and the ribs 3^a of the sections, are positioned differently for the several States. For example, in Fig. 1 sections *b*, *c*, and *d* are 90 adapted to receive the cards of three different States in a single set, namely, Minnesota, Michigan and Ohio. Accordingly, the cards shown in Figs. 5, 6, and 2 have 95 their notches 4 similarly positioned and the ribs 3 of said sections (Fig. 1) are also similarly positioned. It will be noted, however, that the notches 4^a and ribs 3^a of the several States, are differently positioned. 100

Preferably the partitions 2 are hollow in form, being made of sheet metal (Fig. 3), and at their lower edges they are provided with openings 5 adapted to neatly receive the ribs 3 and 3^a. If desired, the ribs 3 of 105 the sections of each set, being similarly located transversely of the case, may be in the form of a single continuous strip, and in this event two aligned openings 5 are provided in the opposite walls 2^a and 2^b of the 110 hollow partitions 2 so that the strip may be extended through the partition. When,

however, the ribs terminate in a partition, as, for instance, the ribs 3^a of each section, and the ribs 3 entering the partitions between sections of different sets, the openings 5 are provided in one wall only of the partition and the ends of the ribs, entered through said opening, abut against the inner surface of the opposite wall. Thus it will be observed that the ribs serve to maintain the partitions spaced apart as well as in upright position. Each section of the index is provided with a divisional card 70 y (Figs. 2 and 3) having a name tab y'.

For the purpose of indicating when a 15 card is properly filed in accordance with a given city, the upper edge of the card is provided with a notch 6, the position of the notch being determined by the first letter of the name of the city (Figs. 4 to 7). Thus, 20 when the cards are properly filed in their several sections of the case, the notches 6 of all cards bearing the names of cities which commence with the same letter, will be in alinement, (Fig. 1) and any card which is 25 not filed according to the proper city, will be quickly detected.

Referring now to Fig. 8, the means for facilitating the accurate formation of the notches in the cards will be described. 30 indicates, generally, a punch of any preferred construction having a table 8 and plunger 9, the latter being provided on its lower end with a triangularly shaped cutter 10 (dotted lines). Upon the table 8 I have provided two tabular guides 11 and 12 for use in notching two different sizes of cards, one guide being located at one side of the plunger and the other upon the other side of the plunger. Each guide may consist of four 35 columns, the States of the United States being arranged into three sets or columns and the letters of the alphabet being arranged in the fourth column.

In the use of the device, a card which is 45 to be filed, for example in the Illinois section a of the case, is placed face down upon the proper guide, as, for instance, 12, and since Illinois is in the first set, the right-hand edge of the card is first brought into 50 alinement with the transverse line 12^a adjacent the words "Set 1" and the punch operated to form a notch 4. Thereupon the same edge of the card is brought into alinement with the corresponding line 12^b adjacent the abbreviated word "Ills." and the 55 punch again operated to form a notch 4^a. To form a notch 6, for the city, in the upper edge of the card, for instance, for the name Aurora, the card is placed face up upon the 60 table 8 with its right-hand edge registering with the line 12^c adjacent the letter "A" on the guide, and the punch operated.

It will be apparent that I have provided a card index of improved construction and 65 arrangement wherein means of a practical

character are provided for effectively guarding against the commission of errors in filing. It will also be observed that means are provided for greatly facilitating the provision of the notches in the cards, thus making 70 practicable the use of the error-preventing means.

I claim as my invention:

1. A card index having, in combination, a plurality of cards, a case, and a plurality 75 of partitions dividing the case into sections for receiving separate groups of cards, each of said sections having a pair of longitudinally extending ribs in its bottom adapted to maintain the partitions spaced apart and 80 in upright position, the ribs of the several sections being spaced at varying distances apart, and the cards of the several groups being provided with notches in their lower edges adapted to receive the ribs of their 85 respective sections.

2. A card index having, in combination, a plurality of cards, a case, and a plurality of partitions dividing the case into sections 90 for receiving separate groups of cards, said 95 sections having longitudinally extending ribs in their bottoms, and the cards to be filed having notches in their lower edges adapted to receive the ribs of the sections in which they are to be filed, said partitions each comprising two spaced walls and having openings in one wall into which ribs are adapted to be entered so as to abut against the opposite wall whereby the partitions are spaced apart and maintained in 100 upright position.

3. A card index having, in combination, a plurality of cards, a case, and a plurality of partitions dividing the case into sections 105 for receiving separate groups of cards, each of said sections having a pair of longitudinally extending ribs in its bottom, and each of said cards to be filed having a pair of notches in its lower edge adapted to receive the ribs of the section in which it is 110 to be filed, said partitions being made hollow in form and having openings near their lower edges adapted to neatly receive the ribs.

4. A card index system comprising in 115 combination with a card index having a plurality of cards, and a case divided into a plurality of separate sections arranged in sets and each adapted to receive a separate group of cards, each card having a pair of notches therein one of which is positioned according to the section in which the card belongs and the other of which is positioned according to the set in which the section belongs, said sections having ribs arranged so 120 that they will enter the notches in the cards when properly filed; means for forming the notches in the cards comprising a cutter and a tabular guide associated therewith, said guide being adapted to indicate the 125 130

proper positions in which the card is to be placed relative to the cutter for the operations of forming said set and section notches.

5. In a card index system including a plurality of cards to be filed, means for forming notches in said cards to guard against the commission of errors in filing, said means comprising a tabular guide and a cutter

associated therewith, said guide being adapted to indicate the proper location of 10 the notches as determined by the data on the cards to be filed.

In testimony whereof, I have hereunto set my hand.

JOHN W. DOWNING.
